UNITED STATES PATENT OFFICE.

JAMES A. HORTON, OF READING, MASSACHUSETTS, ASSIGNOR TO THE WIRE GRIP FASTENING COMPANY, OF BOSTON, MASSACHUSETTS.

MACHINE FOR DRIVING SLUGS.

SPECIFICATION forming part of Letters Patent No. 601,255, dated March 29, 1898.

Application filed March 8, 1897. Serial No. 625,842. (No model.)

To all whom it may concern:

Be it known that I, JAMES A. HORTON, of Reading, in the county of Middlesex and State of Massachusetts, have invented certain new and useful Improvements in Machines for Driving Slugs, of which the following is a specification.

This invention has relation to machines for driving slugs into the heels of boots and shoes, and has for its object to provide certain improvements in the same, whereby slugs of different shapes in cross-section may be placed alternately so as to present a pleasing and ornamental appearance.

15 To this end the invention consists of a machine in which two or more different strips of slugs are fed automatically one by one and alternately to the action of a driver, which inserts them into the heel.

20 It also consists in certain other arrangements and constructions of parts, which are illustrated in the drawings and which I shall now proceed to describe in detail, and then point out in the annexed claims.

25 Reference is to be had to the accompanying drawings, and to the letters marked thereon, forming a part of this specification, the same letters designating the same parts or features, as the case may be, wherever they occur.

30 Of the drawings, Figure 1 represents a front end elevation of a machine embodying my improvements. Fig. 2 represents a side elevation of the same. Fig. 3 represents a longitudinal section through the devices which 35 feed the two sets of slugs to the action of the cutter and the driver. Fig. 4 represents in vertical section the feeding devices just referred to and the adjacent parts, a slug from the upper strip being in position to be driven

40 into the heel. Fig. 5 represents a section of the same, taken on the line 5 5 of Fig. 4. Fig. 6 represents a horizontal section on the line 6 6 of Fig. 4. Fig. 7 represents a section similar to that in Fig. 4, but illustrating a slug on 45 the lower strip as being fed into position to be driven into the heel. Figs. 8 and 9 represent the driver and awl in their two different positions, respectively. Fig. 10 represents the appearance of a heel after the slugs 50 have been driven into place.

Before proceeding to describe the machine illustrated in the drawings I may state that it is selected by me merely for the purpose of

showing one embodiment of the invention, and I do not limit myself in any way to the details of construction, as the invention may be embodied in machines constructed in other ways and operated in a different manner.

55 The machine illustrated has a standard a , upon which is mounted the frame or head a' , having journals a^2 a^3 , in which is mounted a driving-shaft b . Power may be imparted to the said shaft from an outside source by a belt passing around a belt-wheel b^7 or in any other desired way, and upon it are mounted 60 disks b' , b^2 , and b^3 , having cam-grooves, by means of which some of the operative parts of the machine are operated. Upon the end of the shaft is a disk b^4 and upon it on the other side of the grooved disks is a pinion b^5 , 65 both of which actuate other parts of the machine, as I shall now proceed to describe.

d is a swinging guide for the awl-carrier d' , and e is the swinging guide for the driver-carrier, both of which are pivoted at their 70 upper ends on a screw f , threaded into the frame a' , as shown in dotted lines in Figs. 1 and 2. The awl d^2 is suitably clamped in the lower end of the carrier d' , while the driver e^2 is likewise clamped in the lower end of the 75 driver bar or carrier, and they may be alternately swung into the vertical plane of the axis of the shaft b for a purpose to be set forth.

The means for swinging the awl-carrier laterally consists of an arm d^3 , rigidly secured 80 to a rock-shaft d^4 , journaled in a bracket a^3 , extending out from the main frame a' , and an arm d^5 , also rigidly secured to the rock-shaft d^4 and having on its upper end a roller 85 projecting into a cam-slot in the disk b' on 90 the shaft b , before referred to. The lower end of the arm d^3 is bifurcated to extend on both sides of a block d^6 , pivoted to the carrier d by a screw or pin, (these last-named parts being shown in dotted lines in Fig. 1,) so 95 that when the said arm d^3 is swung to the left it rocks the awl-carrier with it. To vary the swing of the awl-carrier, a set-screw d^7 is passed through one of the forks on the end of the arm d^3 and bears against a spring, (not 100 shown,) the said screw being adjustable toward and from the block d^6 .

The awl is reciprocated by an arm d^9 , having a pin d^{10} extending through a slot in the rear of the guide d and engaging the awl-carrier d' , said arm d^9 being rigidly secured to a

rock-shaft d^11 , journaled in brackets a^4 , extending out from the frame, there being also on the rock-shaft an arm d^12 , having a roller extending into the cam-slot in the disk b^3 on the shaft d .

Now it will be seen that the awl-carrier d' may be reciprocated vertically and at the same time be translated bodily from side to side even while a reciprocatory motion is being imparted to it.

Next referring to the driver-bar e' it will be seen that it is reciprocated vertically by a crank-pin e^3 , extending out from the disk b^4 , and a rod e^4 , connecting the pin with a pin e^5 , projecting out from the driver-bar e' through a slot in the face-plate of the driver-bar guide e . The lateral translation or vibration of the driver-bar is effected by an arm e^6 , rigidly secured upon the rock-shaft e^7 , journaled in brackets $a^5 a^5$, extending out from the main frame and also having rigidly secured thereto an arm e^8 , provided on its upper end with a roller projecting into a cam-slot in the disk b^2 on the shaft b .

Preferably the arms d^3 and d^5 and the arms e^6 and e^8 are rigidly secured to their respective rock-shafts d^4 and e^7 by set-screws, and each pair of arms constitutes a lever fulcrumed in the brackets extending out from the main frame.

The driving or power-imparting devices are so timed that the awl is driven into a heel and is carried to the left into the central line of the machine (or the line passing vertically through the axis of the shaft d) and is withdrawn, and the driver is moved from the left to the right into the said line and is driven downward to force a slug into the aperture made by the awl in the heel. The guides d and e for the awl-carrier and the driver-bar carrier are held against transverse movement by a guide-strip g , having its ends extending rearwardly and secured by screws g' to the frame a' .

The slugs which are fed to the action of the driver-bar are formed in two strips or ribbons A B, as shown in Figs. 2, 4, and 7, said slugs having their heads connected together. Preferably the slugs of the two strips are of different shapes in cross-section, as illustrated in Fig. 10—that is to say, the slugs of one strip A may be rectangular in cross-section, while those of the other strip may be diamond-shaped in cross-section—and they are automatically fed forward one by one and alternately to the action of the driver-bar, so that, first, a slug rectangular in section is driven into the heel, and then a slug diamond-shaped in section is driven next to it, and so on, thus giving to the heel an ornamental character.

The strips are wound on rolls, which are not shown, but which may be located at any desired point adjacent the mechanism, from which they are carried to the front end of the machine, where they are respectively engaged by pinions h and i , the teeth of which are

just far enough apart to enter in the apertures between the slugs. The pinions h and i are secured upon sleeves h' i' , respectively, loosely placed upon a shaft j , mounted in a box having a side wall a^{10} , and having top and bottom plates $a^6 a^6$ projecting out from the frame a' .

The sleeve h' has secured to it a ratchet-wheel h^2 , while a similar ratchet-wheel i^2 is secured to the sleeve i' . By means of a suitable mechanism now to be described the pinions h and i have a step-by-step motion imparted to them automatically and alternately, whereby they are caused to force first one strip forward and the other strip forward to the action of a cutter, which I shall describe, and the driver-bar e^2 .

The pinion b^5 on the shaft b intermeshes with a large gear-wheel k , which is rotated once for every two revolutions of the said pinion b^5 . The said wheel k is secured upon the end of a shaft k' , suitably mounted in brackets a^7 projecting out from the frame a' , and has secured to it a path-cam k^2 , into the slot of which projects the roller l' on the end of an arm l^2 , mounted upon the upper end of a rock-shaft l , journaled in bearings a^8 , secured to the main frame a' . At the lower end of the rock-shaft l is a similar arm l^3 , to the outer end of which is pivoted a bar m , which, when the said shaft l is rocked, is reciprocated longitudinally.

The front end of the bar m is pivoted in a sliding block m' , which is adapted to slide in the box on the frame, which has a front plate a^9 .

Mounted loosely upon the pin m^2 , which pivots the end of the bar m to the sliding block m' , are two pawls n and o , the former of which engages the ratchet-wheel h^2 and the latter of which engages the ratchet-wheel i^2 , the said pawls being arranged oppositely or on opposite sides of their respective pawls and being so formed at their ends that a longitudinal movement of the bar m will cause the pawl n to advance the ratchet-wheel h^2 one step while the ratchet-wheel i^2 remains stationary, and the backward movement of the bar m will cause the ratchet-wheel i^2 to move forward one step while the ratchet-wheel h^2 remains stationary. The said pawls are held in yielding engagement with their respective ratchet-wheels by springs p , secured at their outer ends to their respective pawls and at their inner ends to a screw p' , extending through the flanges a^6 . By reason of the slowing-down gearing, which causes the bar m to be reciprocated once for every two reciprocations of the driver-bar, and by reason of the pawls and ratchets just described, which are thus actuated alternately, first a slug on the strip B is presented to the action of the driver-bar e^2 and then a slug on the strip A is presented thereto.

The guide for the driver-bar is extended below the strip g and is provided with an adjustable cutter-blade q , which has a cutting

edge sufficient in length to cut off a slug from either of the strips A or B. The said cutter-blade is located in a recess in the rear face of a plate t , secured to the guide, and is held 5 therein by screws q' , passing through slots in the said plate, being adjusted by means of a screw q^2 , bearing against the edge thereof. Between the cutting edge of the cutter and the edge of the plate is a small space or throat 10 q^3 , (see Figs. 4 to 9, inclusive,) adapted to receive a slug and the driver-bar e^2 .

A stationary blade is secured to the main frame a' and its edge is adapted to coact with the shear edge of the cutter q in cutting off 15 the projecting slug of each strip. The said cutter r extends laterally far enough for the said strips to bear against it as they are fed forward by their respective pinions. It may be adjusted laterally, being formed with a 20 slot r' to receive the screw r^2 , which secures it in place, as shown in Fig. 8. A suitable work-plate s is secured to the frame, so as to project under the awl and driver, and is provided with a slot s' , through which the said 25 awl and driver are projected in turn.

The operation of the machine is as follows: The boot or shoe is placed upon a suitable horn secured to the standard a (and which I have not shown, since such horns are common 30 in the art) and then, power being applied to the shaft b through the medium of the belt-wheel b^2 , the awl-guide being in its farthest position to the right in Fig. 1, the awl is thrust downward into the heel, as shown 35 in Fig. 8, and is carried to the left into the central line of the machine. As this is occurring, the rock-shaft l actuates the bar m and causes the pawl n to rotate the ratchet h^2 one tooth to force the last slug on the strip 40 B forward into the throat and against the plate t on the guide d in front of the cutter q . Then as the awl is being withdrawn the driver-bar guide is fed to the left, cutting off the last slug from the strip B as it moves, until 45 the driver e^2 is in alinement with the aperture made by the awl in the heel. Then the driver forces the slug into the heel. In repeating this operation the same steps are followed, except that since the bar m makes 50 only one reciprocation to two reciprocations of the driver the next movement of the said bar m causes the pawl o to rotate the ratchet-wheel i^2 to feed the strip forward, as shown in Fig. 7, so that the next time the driver-bar descends the last slug from the said strip 55 A will be driven into the heel. These movements are continued until a sufficient number of slugs have been driven into the heel, as shown in Fig. 10.

60 It will be understood, as I have previously stated, that I do not limit myself to the details of construction, and hence I may vary the parts to suit particular requirements, the most important feature of my invention being 65 a mechanism for alternately and automatically feeding strips of slugs forward to the action of the driver-bar, whereby first a

slug from one strip is driven into the heel and then a slug from the other strip is driven in, and so on until a sufficient quantity of 70 slugs of both strips are driven into place.

The machine described is arranged for feeding two strips of slugs alternately; but I have contemplated the feeding of three or more strips by slight changes in the details of construction. 75

I claim—

1. A machine of the character specified, comprising a driver, and mechanism for alternately and automatically advancing the 80 slugs on the end of two or more strips to the action of the driver.

2. A machine of the character specified, comprising a driver, a cutter, and means for alternately imparting a step-by-step movement to strips of slugs, to automatically feed the end slugs of the said strips alternately to the action of the cutter and the driver. 85

3. A machine of the character specified, comprising a driver, a laterally-movable guide 90 for the driver, a cutter mounted on the said guide, means for guiding strips of connected slugs to the machine, and means for automatically advancing said strips alternately to the action of the cutter, whereby the slugs 95 of said strips are presented alternately to the action of the driver.

4. A machine of the character specified, comprising a driver, independent pinions for engaging separate strips of slugs to feed them 100 forward, and means for automatically actuating said pinions alternately, to present said slugs of said strips alternately to said driver.

5. A machine of the character specified, comprising a reciprocating driver, independent 105 pinions for engaging separate strips of slugs to feed them forward, oppositely-acting pawls for imparting an intermittent motion to the pinions, and automatically-acting means for reciprocating said pawls to present 110 the slugs alternately to said driver for each reciprocation thereof.

6. A machine of the character specified, comprising a driver, a power-shaft for actuating said driver, independent pinions for 115 engaging separate strips of slugs to feed them forward, and automatic means operated by said shaft, for imparting motion first to one of said pinions and then to another.

7. A machine of the character specified 120 comprising a reciprocating driver, a pivoted guide therefor, means for feeding two or more strips of slugs alternately to the guide, means on the guide for cutting off a slug, and means for oscillating said guide. 125

In testimony whereof I have signed my name to this specification, in the presence of two subscribing witnesses, this 20th day of February, A. D. 1897.

JAMES A. HORTON.
